EDNA J. SIDBURY, OF NEW YORK, N. Y.

HOT-WATER HEATER.

1,249,219.

Specification of Letters Patent. Patented Dec. 4, 1917.

Application filed April 13, 1917. Serial No. 161,806.

To all whom it may concern:

Be it known that I, EDNA J. SIDBURY, a citizen of the United States, residing at New York, in the county of New York and State 5 of New York, have invented new and useful Improvements in Hot-Water Heaters, of which the following is a specification.

This invention is a hot water heater, more particularly adapted for domestic use, 10 wherein the refuse such as is accumulated in the household may be burned to furnish the heat in addition to the other fuel.

The invention contemplates the use of a down-draft type of furnace having a water 15 jacket to which may be connected suitable service pipes and the usual household boiler.

One object of the invention is to provide for the burning of the refuse in a convenient furnace and utilizing the heat of such burning for the heating of water for domestic 20 purposes.

The invention broadly stated, comprises a down-draft furnace that is provided with a water jacket, a flue leading from the combustion space, inlet and outlet pipes connecting the water jacket, and means to utilize the water after heating in a domestic boiler or suitable radiator.

One practical form of construction will 30 be described and illustrated in the accompanying drawing, in which:—

Figure 1 is a vertical sectional view of the heater connected to a household boiler; and

Fig. 2 is an elevation of the heater connected to a radiator.

In the embodiment shown in the accompanying drawing, the heater may be cylindrical in form and is provided with the spaced apart vertical walls 5 and 6. The 40 space between the walls 5 and 6, indicated at 7, provides a water jacket which entirely surrounds the fire pot in which the fuel 8 is disposed. At some convenient point adjacent the bottom wall 9 of the heater, there

45 is a hand hole which extends into the fire pot and is closed by means of the cover 10. This cover 10 may be secured in any usual manner to the heater, so as to prevent the ashes and burned product from falling out

50 accidentally. As shown, the hand hole 11 passes through the walls 5 and 6, but is not in communication therewith, as the hand hole is surrounded by a suitable connecting piece indicated at 12, which being formed 55 integrally with the walls prevents leakage of water.

To support the heater from the floor, the legs 13 may be employed, which may be of any usual or customary type of construction suitable for this purpose. They may be 60 removably secured to the bottom wall 9, if so desired. As shown, it is preferred to construct the walls 5 and 6 and the bottom wall 9 as a unitary structure, that is to say being cast in one piece in one operation, 65 although for more practical purposes the bottom wall 9 may be formed as a head that may be secured to the walls 5 and 6 in the usual or customary manner.

The heater is closed by means of a top 14, 70 which as shown is provided with a central opening that is closed by means of the cover 15, and the fuel opening that is closed by the cover 14^a. Secured to the under side of the top 14 and adjacent the central opening 75 is a conical draft member 16, which has at its lower depending end a cylindrical sleeve portion 17 to provide a sliding and adjustable connection with the down-draft air tube 18. The member 16 is provided with a 80 flange 16^a so that it may be secured to the under side of the top plate or wall 14. The draft air tube 18 may be raised and lowered in accordance with the amount of fuel within the fire pot of the heater. This will permit of the introduction of air at the best point for burning the fuel.

The cover 15 may be provided with suitable openings that may be closed or opened as the requirements of combustion necessitate. Thus the top 15 may be employed as a damper, although if desired it may be made solid and removable from the opening. At another point in the top there is another opening indicated at 19, that is surrounded 90 by a collar 20, to which is secured a flue pipe 21 having a suitable damper 22 disposed therein. This flue pipe 21 communicates with the combustion space indicated at A.

The top 14 is provided with suitable annular flanges indicated at 23 and 24. These flanges 23 and 24 are adapted to coöperate with the walls 5 and 6 and be secured thereto in any convenient or workmanlike manner. 100 The manner of fitting this top upon the side walls will be such that a water-tight joint is formed therebetween to prevent leakage.

At a suitable point or place on the top wall or plate 14, there is formed a port that provides an outlet for the heated water. The outlet pipe is indicated at 25, and its

point of attachment to the top wall or boiler 14 and the water jacket 7 is indicated at 26. The outlet pipe 25 is connected to a boiler 27 in any suitable or usual manner, the point of 5 attachment being shown in Fig. 1 at 28.

Communicating with this boiler are suitable service pipes indicated at 29 and 30, which serve to permit water to be fed to the water jacket 7, and also to be withdrawn 10 from the boiler 27. Secured to the bottom of the boiler 27 is an inlet pipe 31 that has a suitable connection with the wall 5 so that it may communicate directly with the water jacket 7 to fill said jacket with water, the 15 point of connection being indicated at 32, and this connection may be of the usual or customary type. The boiler 27 is supported upon the usual or customary stand indicated at 33, which has a foot plate 34 resting upon 20 the floor indicated at 35.

In Fig. 2 there is shown a modification which adapts the heater to heat water for a radiating system, one of the radiators being shown at 36. In this figure, the inlet pipe 25 is indicated at 31, and the outlet pipe at 25. These two pipes serve to connect the heater and its water jacket to the service pipes. The pipe 37 connected with the upper portion of the water jacket serves to direct the 30 heated water to the top of the radiator 36. A valve 38 may be disposed in this pipe so as to restrict the passage of the heated water to the radiator.

The lower portion of this radiator 36 is 35 connected to the lower portion of the water jacket by means of an inlet pipe indicated at 39. The pipe 39 may also be provided with a valve if so desired, the valve being indicated at 40.

40 As shown in this figure, the cover 10 of Fig. 1 may be formed as a door having a hinged connection with the wall 5, the hinged connection being indicated at 41. To maintain the door in closed position, a 45 latch 42 may be employed, which is provided with a suitable keeper indicated at 43.

While the device has been shown as being more particularly adapted for heating water, the same may be utilized for the production 50 of steam with slight changes in form and construction, while the essential or main details remain the same. The change may be effected by the employment of additional means for regulating the supply of water to the jacket 7. As these means do not come within the scope of this invention, they are not shown or described.

As this device is more particularly adapted 60 for household use, the heater may be employed for burning refuse, such as newspapers and garbage in connection with solid fuel. This utilization of the waste products of the house will enable the heater to be operated in an economical manner. The provision 65 of the down-draft tube type will en-

able the user to increase the rate of combustion of the fuel with very little effort. In this type of heater, the mere opening of the damper disposed within the cover 15 will permit air to enter below the point of combustion and proceed upward through the fuel and by means of the oxygen supplied thereto will increase the rate of combustion to the desired point, and the maximum amount of heat units will be evolved.

The provision of the water jacket surrounding the fire box and the combustion space maintains the water in the closest contact with the heat emitting substances, and the combustion chamber A being filled with 80 heated gases communicates its heat to the wall 6. The water jacket 7, being filled with water, abstracts the heat therefrom, and is heated thereby.

The down-draft tube type of heater is 85 adapted to produce an intense fire and a rapid rate of combustion by reason of its construction, and from this construction a large amount of air is consumed producing a large number of heat units. The water 90 disposed within the jacket 7 is very quickly heated, and after being heated passes to the boiler 14 in a more or less natural manner so that there is a constant circulation within the jacket 7 by the water.

95 Minor changes in the form, proportions, and details of construction may be resorted to without departing from the spirit of the invention or the scope of the appended claims.

100 What is claimed as new is:—

1. A water heater of the down-draft type including an air tube and flue, comprising a shell having vertically disposed concentric walls to provide a water jacket therebetween, a bottom plate for said walls formed integrally therewith, a hand hole extending through the walls for cleaning the heater of refuse and burned solid products of combustion, a top plate removably secured to the walls and having annular flanges to co-operate with the walls to form a water-tight joint therebetween, means to provide for water connections with the jacket, the innermost wall forming a combustion chamber, and a down-draft tube secured to the top plate and terminating adjacent the lower zone of combustion.

115 2. A water heater of the down-draft type including an air tube and flue, comprising a shell having spaced vertical walls to provide a water jacket therebetween, the inner vertical wall constituting the wall of a combustion chamber, ports for the water jacket to provide for water connections, a hand 120 hole for cleaning the fire pot, a down-draft tube, and means connected with the tube for adjusting the lower end of the tube relative to the point of combustion.

125 3. A water heater of the down-draft type 130

comprising a shell having concentric walls, adapted to form a water jacket therebetween, a top plate therefor, a bottom plate for said walls and forming a unitary structure therewith, a hand hole having a removable cover to permit of the cleaning of the remaining products of combustion, means to provide for water connections, a down draft tube having a cone-shaped member secured

to the top plate, and terminating in a cylindrical sleeve portion, and an air tube to cooperate with the sleeve portion of the cone-shaped member, said sleeve affording a bearing to permit of the adjustment of the air tube relative to the top and the point of combustion.

In testimony whereof I affix my signature.

EDNA J. SIDBURY.
